Primary Examiner — Ruth McInroy(74) *Attorney, Agent, or Firm* — Morrison & Foerster LLP(57) **CLAIM**

We claim the ornamental design for a part of a vacuum cleaner, as shown and described.

DESCRIPTION

FIG. 1 is a perspective view of a part of a vacuum cleaner showing our new design;

FIG. 2 is a side view thereof;

FIG. 3 is a side view of the opposite side of FIG. 2;

FIG. 4 is a top view thereof;

FIG. 5 is a bottom thereof;

FIG. 6 is a front view thereof; and,

FIG. 7 is a rear view thereof.

The details shown in broken lines form no part of the claimed design.

1 Claim, 5 Drawing Sheets(56)
